UNITED STATES PATENT OFFICE.

JOSEPH J. ADGATE, OF NEW YORK, N. Y.

DESIGN FOR CASTERS.

Specification forming part of Design No. **11,166**, dated April 22, 1879; application filed March 25, 1879.
[Term of patent 7 years.]

To all whom it may concern:

Be it known that I, JOSEPH J. ADGATE, of New York, in the county of New York, and in the State of New York, have invented certain new and useful Improvements in Design for Furniture-Caster; and do hereby declare that the following is a full, clear, and exact description thereof, reference being had to the accompanying drawings, and to the letters of reference marked thereon, making a part of this specification.

The nature of my design is fully illustrated in the accompanying drawing, which represents a side elevation of my ball-caster.

In the drawing, A is the ball, inserted and held in a cage, from which the spindle B pro-

jects. The cage consists of a top plate or head, C, with a series of arms, D D, extending downward, said arms being connected by a band, F, and the arms projected below the band to form the points a a.

What I claim is—

The design for cage for ball-caster, consisting of the head C, arms D, band F, and points a, substantially as shown and described.

In testimony that I claim the foregoing I have hereunto set my hand this 20th day of March, 1879.

JOSEPH J. ADGATE.
